(57) **CLAIM**

The ornamental design for a USB connector for racks, sections and panel devices, applicable to standards of USB2.0/USB3.0, type A, as shown and described.

DESCRIPTION

FIG. 1 is a bottom perspective view of a USB connector for racks, sections and panel devices, applicable to standards of USB2.0/USB3.0, type A, showing my new design; FIG. 2 is a top perspective view thereof;

FIG. 3 is a rear view thereof;

FIG. 4 is a front view thereof;

FIG. 5 is a left side view thereof. The right side view is a mirror image of the left side view thereof;

FIG. 6 is a bottom plan view thereof; and,

FIG. 7 is a top plan view thereof.
